UNITED STATES PATENT OFFICE.

PETER BEHR, OF HANOVER, GERMANY.

SURGICAL SEWING INSTRUMENT.

No. 834,042.

Specification of Letters Patent.

Patented Oct. 23, 1906.

Application filed October 13, 1905. Serial No. 282,623.

To all whom it may concern:

Be it known that I, PETER BEHR, doctor of medicine, a subject of the German Emperor, residing at No. 9 Goethestrasse, Hanover, 5 in the German Empire, have invented certain new and useful Improvements in Surgical Sewing Instruments, of which the following is a specification.

The present invention relates to a surgical sewing instrument having an antiseptic thread-guide, this instrument being distinguished from those hitherto known by the fact that all parts of the needle-holder are easily removable and adapted to be thoroughly cleansed, since there are no edges or holes to which micro-organisms might adhere, and, further, the improved instrument after sterilizing guarantees the antiseptic condition of the sterilized thread, since owing to the position of the latter it is completely prevented during normal use from accidental contact with the hands of the operator or other objects until its entrance into the edge of the wound to be sewed. At the same time the improved needle having the sewing-thread of any desired length inclosed in the needle-holder permits of making any desired number of single-knot seams without necessitating the removal of the needle from its holder and rethreading of the needle, thus saving considerable time and dispensing with assistance to a great extent.

The invention is represented in the annexed drawings, in which—

Figure 1 is a side elevation of the complete instrument. Fig. 2 is a plan view thereof. Fig. 3 is a face view of one member of the holder, showing the thread inserted therein. Fig. 4 is a detailed view in perspective of a 40 clamping-lever for securing the two members of the holder together, and Fig. 5 is a side view of the needle.

The two members or halves *a* *b* of the holder or handle are pivoted or hinged together at one end, as at *c*, and at their other ends are adapted to grip the needle *d*. The clamping-lever *e* is pivotally mounted in the jaws *e'* and is adapted to press the member *a* against the member *b*, and thus insure the needle *d* being securely held.

The method of pivoting the two members and the construction of the clamping-lever *e* may vary according to requirements.

At the rear part of the needle-holder the two members *a* and *b* are not solid, but hol-

lowed out to a mere shell *h*, so that they may receive a reel or coil of thread or thread holder or case *f* containing the latter. The case is held within the hollowed portion by means of lugs or projections *g*, which may be either slid into the holder members or be rigidly connected thereto or integral therewith. The thread-holder *f* is assumed to be one of the known sterilized packages sold in commerce, but the thread must be adapted to be easily unwound therefrom. Other suitable coils or reels of thread can obviously be inserted and sterilized together with the instrument.

The thread *i* passes from the thread-receptacle through a groove *k*, formed in one of the members—for instance, *b*—said groove being covered by the other member *a*, and at a short distance in front of the needle the groove is provided with a lateral opening *k'*, Fig. 3, through which the thread *i* makes its exit. The needle *d*, which may be of various shapes according to the use to which it is to be put, is provided at its point with an eye *l*, communicating with a longitudinal slot *m*, for reception of the thread.

The instrument is used as follows: The thread-receptacle *f* is first inserted in the hollowed part *h* of one member and the thread *i* passed through the groove *k*, whereupon the other member is folded or placed against the first member and the clamping-lever *c* raised. After inserting the needle *d* the clamping-lever *e* is pressed down, by which the needle is secured. A natural elasticity is obtained by the shell-shaped construction of the holder members *a* and *b*, so that the holder automatically adjusts or adapts itself to the thickness of the needle in such a manner that a thicker needle, the use of which naturally requires the exertion of greater force than a thin one, is more securely clamped, according to its thickness. In the case illustrated the clamping-lever *e* is formed as an angle-lever, but it may be formed as an eccentric-lever or the like. The thread *i* passed through the groove *k* and projecting at the end of the instrument is passed into the slot *m* in the needle and the eye *l* threaded. When the whole instrument has been finally sterilized, the thread can be used until consumed without again touching it with the hand, except when tying a knot. By passing the thread through the stitches of the seam it is carried along to the opposite

end and there held fast, the needle being then pulled back along the thread unwinding from the receptacle and the thread cut to the necessary length. The seam is then 5 complete. The needle is again ready for use without removing same from the holder, and the thread in the wound is completely antiseptic. After tying the ends of the thread the wound is closed.

10 Owing to the simplicity of the instrument, the great saving of time in stitching the wound, and the certainty of a completely-antiseptic sewing-thread, the present invention is a great advance in the surgical treatment 15 of wounds.

I claim as my invention—

1. In a surgical sewing instrument, a longitudinally-divided holder consisting of two separable members each having a hollowed 20 portion coöoperating to form a thread-receptacle and an extended portion coöperating to form a needle-clamp combined with means

for clamping said members together substantially as described.

2. A surgical sewing instrument comprising a longitudinally-divided holder consisting of two hinged members each having at one end a hollowed portion coöperating to form a thread-receptacle and one of said members having a longitudinal thread-groove in communication with said receptacle, means for holding the thread in the latter, a needle held between the members at the ends opposite the thread-receptacle and in communication with said groove, and means for clamping said members together substantially as described. 25 30 35

In witness whereof I have signed this specification in the presence of two witnesses.

PETER BEHR.
